AUTOMATIC TIMEKEEPING REGULATORS

Robert E. Le Blanc, Silver Spring, Md., assignor to The Hamilton Watch Company, Lancaster, Pa., a corporation of Pennsylvania

Filed Sept. 24, 1959, Ser. No. 842,119

12 Claims. (Cl. 58—85.5)

This invention relates to automatic regulators for timepieces and more particularly to timepieces which are automatically regulated by means of a delayed action mechanism and which are provided with a lock-out mechanism for limiting the frequency of regulation.

There has been a growing trend in the timepiece industry to produce timepieces equipped for automatic regulation to correct inaccuracies in timekeeping. In conventional timepieces, it has been the ordinary practice to provide a regulating mechanism which is accessible from either inside the case or from the back of the timepiece. In certain types of timepieces, such as automobile clocks, however, the mounting of the clock makes it difficult to provide a readily accessible regulating mechanism which is not also subject to undesirable tampering, such as by children. This problem has been particularly compounded by the fact that it has most usually been the desire of either the clock or the automobile manufacturer to provide an automatic regulating mechanism requiring a minimum of conscious effort on the part of the operator, which desire has usually been satisfied by so incorporating the regulating mechanism in the timepiece that regulation is effected each time the hands of the clock are set. If regulation is automatically effected each time the hands of the clock are set by means of a readily accessible adjusting mechanism, tampering of the clock is quite apt to result in over-regulation and ultimately in an inaccurate timepiece.

A still additional problem is created by the fact that it is often desirable to adjust the setting of the hands of the timepiece for reasons other than faulty timekeeping, i.e. when passing from one time zone to another or when the clock has stopped due to failure to wind or because of a power failure. It is thus essential that the regulating mechanism be so constructed that regulation will not be significantly effected when adjustments of the latter nature are made.

It is accordingly a primary object of the present invention to provide an improved automatic regulating mechanism for a timepiece which is readily accessible and yet will minimize the effects of tampering.

It is another principal object of the present invention to provide an automatic regulator for a timepiece which will limit the maximum regulation per adjustment to compensate for non-regulatory adjustments of the timepiece.

It is another object of the present invention to provide an improved automatic regulating mechanism for a timepiece in which the regulation of the timepiece takes place automatically and to the extent regulated at a single point in time subsequent to the adjustment of the hands of the timepiece and which tends to prevent additional regulation of the mechanism until such time as said first mentioned regulation has taken place.

It is yet another object of the present invention to provide an improved automatic regulating means for a timepiece which essentially comprises a novel cam means and associated stop elements which jointly cooperate to effect delayed regulation of the timepiece and to provide a lock-out feature to tend to prevent reregulation until such time as said delayed regulation has taken place, without the need for conventional stops and limits heretofore used.

2

These and further objects and advantages of the present invention will become more apparent upon reference to the following specification, appended claims and drawings wherein:

5 FIGURE 1 is a perspective view of the automatic regulating mechanism of the present invention, with parts broken away for clarity of illustration; and

10 FIGURE 2 is a fragmentary bottom plan view of the mechanism shown in FIGURE 1, showing the regulating position of a novel cam member forming an important element of the instant invention.

15 As shown in FIGURE 1 of the drawing, the novel regulation mechanism of the instant invention comprises a vertically movable set stem 8 having a set stem knob 9 at its outer end and carrying a pinion 10 having a disc 12 rigidly fixed to its upper surface. Set stem 8 is biased into the position shown in FIGURE 1 by means of a coil spring 13 which is interposed between set stem knob 9 and frame 14 of the timepiece. An idler shaft 16, which 20 is also movable in a vertical direction, carries a gear 18 which meshes with pinion 10. As clearly shown in FIGURE 1, disc 12 extends over and beyond the edge of gear 18 so that when set stem 8 is depressed downwardly, disc 12 will carry gear 18 with it. A minute wheel 20 mounted on shaft 21 is positioned to mesh with the pinion 10 when set stem 8 is in its fully depressed position. Idler shaft 16 is biased vertically upwardly by a suitable provided spring mounting (not shown) so that gear 18 will remain in engagement with pinion 10 regardless of the position of set stem 8.

25 Idler shaft 16 is resiliently urged toward a horizontally centered position by means of a U-shaped spring 22 engaging a pair of pins 24 on a disc 26 which is fixed to idler shaft 16 at a point above gear 18. It will be noted that 30 spring 22 will be effective to return the idler shaft 16 to either of two horizontally centered positions separated by 180° from one another, depending upon the amount of rotation of the shaft before it is released for such return.

35 Secured to the underside of gear 18 is a depending skirt 28 which defines a cam surface. As best shown in FIGURE 2, this surface is provided with a profile which repeats itself on either side of line C—C longitudinally dividing skirt 28 and which is provided with non-circular 40 portions 31, 33, 35 and 37 (i.e., defining a locus of points non-equidistant from the center 29 of skirt 28). As will be explained more fully below, at least a portion of the cam profile consists of circular portions such as are designated by the numerals 39 and 41.

45 A bent lever 30 is pivotally mounted intermediate its ends on a pivot 31 and has an elongated spring 32 secured to the free end of its lever arm 34 in a conventional manner. The other end of spring 32 is received in a post 36 which is secured to the clock frame. Mounted on arm 50 34 longitudinally displaced from the free end thereof are a pair of spaced stop members 38. Gear 18, pinion 10, minute wheel 20 and lever 30 are so positioned relative to one another that as set stem 8 is depressed, pinion 10 will mesh with minute wheel 20 simultaneously with the 55 positioning of an edge of skirt 28 in the space between stop members 38. As is apparent from the drawing and from the foregoing description, rotation of set stem 8 in its depressed position will cause movement of lever 30 either in the direction A or the direction B, depending upon the direction of rotation of the set stem and the 60 configuration of skirt 28.

65 Lever arm 34 of lever 30 is provided with a longitudinal slot 40 in which a pin 42 on a rack plate 44 rides. Rack plate 44 is provided with a slot 46 which, in turn, receives a pin 48 mounted on clock frame 45. An elongated spring 50 extends between pin 48 and a second pin 52.

70

Lever arm 43 of lever 30 is provided with a longitudinal slot 40 in which a pin 42 on a rack plate 44 rides. Rack plate 44 is provided with a slot 46 which, in turn, receives a pin 48 mounted on clock frame 45. An elongated spring 50 extends between pin 48 and a second pin 52.

which is also mounted on the clock frame 45. A second pin 54 on rack plate 44 engages spring 50 so as to bow the spring as shown in FIGURE 1, to normally urge rack plate 44 in a clockwise direction about pin 48 toward a gear 56 which is operatively mounted to move a rate regulator 57 of conventional construction.

A detent 58 is biased into engagement with the teeth 59 of rack plate 44 by means of a coil spring 60. Detent 58 has depending therefrom a pin 62 which is elongated in FIGURE 1 merely for ease of illustration. The hour wheel 64 on shaft 67 carries a pin 66 which is adapted to engage pin 62, in the course of rotation of the wheel, thereby tending to push detent 58 away from teeth 59 of rack plate 44.

In operation, set stem knob 9 is depressed to bring pinion 10 into engagement with minute wheel 20 and, simultaneously, to depress gear 18 so that an edge of skirt 28 passes between stop members 38. Since pinion 10 is in engagement with wheel 20, rotation of set stem knob 9 will result in adjustment of the hands of the timepiece. By proper selection of the cam profile of skirt 28, it is clear that the accompanying rotation of gear 18 will also cause lever arm 34 to be pivoted about pivot point 31 by an angular distance proportional to the adjustment made in the position of the hands of the timepiece. Due to the rotation of lever arm 34, spring 32 is placed under tension and tends to urge lever 30 back to its normal position.

Depending upon the direction of rotation of set stem knob 9 and the configuration of skirt 28, lever arm 43 of lever 30 will move either in the direction A or in the direction B. As lever arm 43 rotates about pivot point 31, rack plate 44 will be caused to slide past pin 48 either to the right or to the left in an amount proportional to the angular movement of lever arm 43 which is in turn a function of the shape of the cam surface of skirt 28. As it does so, the holding effect of detent 58 will be overcome whereupon the detent will be displaced longitudinally of the teeth 59 in one direction or the other, depending upon the direction of movement of the rack plate. Gear 56 is separated sufficiently from rack plate 44 so that teeth 59 of the rack plate are separated from gear 56 while detent 58 is acting upon the rack plate but spring 50 is bowed sufficiently to urge rack plate 44 into engagement with gear 56 when detent 58 is removed.

When the desired adjustment of the hands of the timepiece has been made, set stem knob 9 is released, and since both set stem 8 and idler shaft 16 are upwardly spring biased, both idler shaft 16 and set stem knob 9 will return to their normal, disengaged position. At the same time, pinion 10 will become disengaged from minute wheel 20 and skirt 28 will be removed from between stop members 38. With the holding action of stop members 38 removed, U-shaped spring 22 will return idler shaft 16 to its centered or normal position. However, though the manual rotation of set stem knob 9 provided sufficient force to overcome the holding effect of detent 58 to permit movement of rack plate 44, detent 58 provides sufficient holding power in its new position with respect to teeth 59 to prevent further movement of the rack plate or engagement of gear 56 by teeth 59. For this reason, no regulation of the timepiece will take place at this time, notwithstanding the fact that set stem knob 9 and its associated elements have been returned to their normal position out of engagement with stop members 38.

As the hour wheel 64 rotates sufficiently so that its pin 66 engages the pin 62 depending from detent 58, detent 58 will slowly be pushed back away from rack plate 44. When the hour wheel 64 has rotated sufficiently, its pin 66 will push detent 58 a sufficient distance away from rack plate 44 to permit the engagement of its teeth 59 with gear 56 by means of the force of spring 50. As soon as the detent has cleared teeth 59, the tension in spring 32 will cause it to return to its

5 normal position, rotating lever 30 about its pivot 31, which in turn will move rack plate 44 and rotate regulating gear 56 through a distance proportional to the original angular movement of lever 30.

Once the timepiece has been regulated, it may be reregulated by repeating the sequence of steps described above. It is to be noted, however, that before the actual regulating step takes place, i.e., before such time as the hour wheel 64 rotates sufficiently to disengage detent 58 from rack plate 44, the reregulation of the timepiece is inhibited once the set stem knob 9 has been returned to its normal, disengaged position. This results from the fact that upon disengagement of skirt 28 from between stop members 38, the skirt is rotated back to its normal, centered position by means of spring 22, whereas stop members 38 remain in their adjusted position. If set stem knob 9 is then depressed as above described, skirt 28 will hit the top of the stop members and since no further regulation may be obtained unless skirt 28 passes 15 between stop members 38, no further regulation may take place. It is not until the delayed regulation takes place and the entire mechanism is reset to its normal position by sufficient rotation of hour wheel 64 that additional regulation may be effected, as described above.

20 As aforesaid, only a portion of the cam surface formed by skirt 28 is non-circular in form, the remaining portions of the cam surface being equidistant from the center 29 of skirt 28. Since rotation of lever 30 will take place only by passage of the non-circular portions 25 of the cam surface between stop members 38, no regulation will take place throughout the range of circularity of the cam surface. In view of this fact, it is possible to limit the maximum regulation which may be effected at any one setting of the timepiece by limiting the portion 30 of the cam surface which is non-circular so that after the desired maximum regulation has taken place, a circular portion of the skirt will pass between stop members 38. Since, as aforesaid, timepieces are often adjusted for non-corrective purposes, the magnitude of regulation 35 during any such adjustment will never exceed the predetermined maximum and the undesired regulation can later be eliminated by readjusting and reregulating the mechanism in the manner above described.

40 It was also pointed out above that the cam surface 45 repeats itself on each side of the line C-C longitudinally dividing skirt 28 (see FIGURE 2). Thus, in the event rotation of set stem knob 9 for any given adjustment is sufficiently great to rotate idler shaft 16 more than 90° (in which case the idler shaft will be centered to its 50 second position, 180° out of phase with its first position, when set stem knob 9 is returned to its normal position) skirt 28 will still present a cam surface for entry between stop members 38 upon the next adjustment of the timepiece.

55 The mechanism described above provides numerous advantages. Not only is the instant automatic regulating mechanism fully automatic without the necessity for conscious effort on the part of the operator, but it also tends to prevent further injection of regulation until the 60 initially injected regulation has been accomplished. That is to say, while it is possible to rotate the set knob 9 until the skirt 28 is in a position to enter the space between stops 38 and thereby effect a second injection of regulation before the first has been accomplished, this 65 will not occur in a majority of instances because release of the knob 9 would allow spring 22 to return the skirt to the illustrated position. For the most part, undesired re-regulation would be accomplished only by holding the knob 9 down and then rotating it until the skirt enters the space between the stops. It is improbable that an adult would do this and even a child would accomplish it only by chance or prolonged tampering. Thus, while the device does not absolutely prevent injection of unwanted re-regulation, it tends to prevent it.

70 In addition, in the event the timepiece has been acci-

dentially overadjusted, the novel regulating mechanism of the instant invention permits immediate readjustment regardless of the magnitude of the overadjustment, so long as the set stem knob has not been returned to its normal position; and the delayed action mechanism permits such adjustment and readjustment with only a single regulation operation.

The invention may be embodied in other specific forms without departing from the spirit or essential characteristics thereof. For example, while the return spring for set stem 8 has been illustrated as a coil spring located externally of the clock frame, the spring may also be positioned within the clock frame or may, if desired, take other forms such as the flat spring disclosed in assignee's copending application, Serial No. 840,373 filed September 16, 1959, now abandoned. Also, pin 54 may be rotatable about its vertical axis on rack plate 44 to reduce friction.

The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a timepiece comprising: time measuring means; time indicating means actuated by said time measuring means; time setting means for setting said time indicating means to any position in its time indicating range; rate regulating means for regulating the rate of said time measuring means; automatic regulating means including cam means and cam follower means, a drive member positioned in a normal position by a spring such that the spring is stressed by movement of said drive member from said normal position, and means for holding said drive member in position against the stress of said spring; said cam means being driveable by said time setting means and being drivingly engageable with said cam follower means when said cam means and cam follower means are in certain predetermined relative positions and being drivingly unengageable with said cam follower means when said cam means and cam follower means are in other relative positions, said cam means being effective when in driving engagement with said cam follower means to move said drive member and stress said spring, the amount of movement of said drive member being a function of movement of said time setting means to move said time indicating means for releasing said means for holding said drive member in position against the stress of said spring whereby said drive member moves; said last named movement of said drive member being effective to adjust said rate regulating means to vary the rate of said time measuring means.

2. In a timepiece comprising: time measuring means; time indicating means actuated by said time measuring means; time setting means for setting said time indicating means to any position in its time indicating range; rate regulating means for regulating the rate of said time measuring means; automatic regulating means including cam means and cam follower means, a drive member positioned in a normal position by a spring such that the spring is stressed by movement of said drive member from said normal position, and means for holding said drive member in position against the stress of said spring; said cam means being driveable by said time setting means and being drivingly engageable with said cam follower means when said cam means and cam follower means are in certain predetermined relative positions and being drivingly unengageable with said cam follower means when said cam means and cam follower

means are in other relative positions, said cam means being effective when in driving engagement with said cam follower means to move said drive member and stress said spring, the amount of movement of said drive member being a function of movement of said time setting means to move said time indicating means; said automatic regulating means including triggering means driven by said time measuring means subsequent to movement of said time setting means to move said time indicating means for releasing said means for holding said drive member in position against the stress of said spring whereby said drive member moves; said last named movement of said drive member being effective to adjust said rate regulating means to vary the rate of said time measuring means.

3. In a timepiece comprising: time measuring means; time indicating means actuated by said time measuring means; time setting means for setting said time indicating means to any position in its time indicating range; rate regulating means for regulating the rate of said time measuring means; automatic regulating means including cam means and cam follower means, a drive member positioned in a normal position by a spring such that the spring is stressed by movement of said drive member from said normal position, and means for holding said drive member in position against the stress of said spring; said cam means being driveable by said time setting means and being drivingly engageable with said cam follower means when said cam means and cam follower means are in certain predetermined relative positions and being drivingly unengageable with said cam follower means when said cam means and cam follower means are in other relative positions, said cam means being effective when in driving engagement with said cam follower means to move said drive member and stress said spring, the amount of movement of said drive member being a function of movement of said time setting means to move said time indicating means; said automatic regulating means including triggering means driven by said time measuring means subsequent to movement of said time setting means to move said time indicating means for releasing said means for holding said drive member in position against the stress of said spring whereby said drive member immediately moves; said last named movement of said drive member being effective to adjust said rate regulating means to vary the rate of said time measuring means.

4. In a time piece as set out in claim 1, said cam means having certain portions thereof which cause movement of said cam follower means when said cam means and said cam follower means are in driving engagement and said cam means is moved, and having other portions which do not cause substantial movement of said cam follower means when said cam means is moved.

5. In a timepiece as set out in claim 4, said cam means having plural certain portions and plural other portions.

6. In a timepiece as set out in claim 5, said plural certain portions being disposed substantially 180° from one another and said plural other portions being disposed substantially 180° from one another.

7. In a timepiece comprising: time measuring means; time indicating means actuated by said time measuring means; time setting means for setting said time indicating means to any position in its time indicating range; rate regulating means for regulating the rate of said time measuring means; automatic regulating means including cam means and cam follower means; a drive member movable into driving engagement with said rate regulator means and being positioned in a normal position by a spring such that the spring is stressed by movement of said drive member from said normal position, and means for holding said drive member in position against the stress of said spring; said cam means being driveable by said time setting means and being drivingly

engageable with said cam follower means when said cam means and cam follower means are in certain predetermined relative positions and being drivingly unengageable with said cam follower means when said cam means and cam follower means are in other relative positions, said cam means being effective when in driving engagement with said cam follower means to move said drive member and stress said spring, the amount of movement of said drive member being a function of movement of said time setting means to move said time indicating means; said automatic regulating means including means for moving said drive member into driving engagement with said rate regulating means, and also including triggering means operative subsequent to movement of said time setting means to move said time indicating means for releasing said means for holding said drive member in position against the stress of said spring whereby said drive member moves into driving engagement with said rate regulating means and moves to drive said rate regulating means; said last named movement of said drive member being effective to adjust said rate regulating means to vary the rate of said time measuring means.

8. A device for automatic regulation of the escapement hair spring of a clock in connection with the setting of the hands of said clock comprising a rotatable adjusting shaft for setting the hands of said clock to any position in its time indicating range, rate regulating means for said hair spring, drive means held in a normal position by spring means, said spring means being stressed when said drive means is moved from said normal position, locking means for holding said drive means in position against the stress of said spring means, said drive means being movable into and out of driving engagement with said rate regulating means, means coupling said drive means to said adjusting shaft to move

5

said drive means when it is out of driving engagement with said rate regulating means, and means operative subsequent to said last named movement of said drive means to move said drive means into engagement with said rate regulating means and to release said locking means whereby said drive means moves and drives said rate regulating means.

9. A device as set out in claim 8 wherein said means coupling said drive means to said adjusting shaft causes said drive means to move as a non-linear function of movement of said drive shaft.

10. A device as set out in claim 8 wherein said means coupling said drive means to said adjusting shaft causes said drive means to move as a discontinuous function of movement of said drive shaft.

11. A device as set out in claim 8 wherein said coupling means includes cam means and cam follower means movable into and out of driving engagement.

12. A device as set out in claim 11 wherein said cam means and said cam follower means are incapable of moving into driving engagement in certain relative positions of said cam means and said cam follower means.
